UNITED STATES PATENT OFFICE.

ALBERT CHAMPION, OF FLINT, MICHIGAN, ASSIGNOR TO A C SPARK PLUG COMPANY, OF FLINT, MICHIGAN, A CORPORATION OF MICHIGAN.

SELF-CLEANING SPARK PLUG.

Application filed October 28, 1922. Serial No. 597,611.

To all whom it may concern:

Be it known that I, ALBERT CHAMPION, a citizen of the Republic of France and a resident of Flint, county of Genesee, and 5 State of Michigan, have invented certain new and useful Improvements in Self-Cleaning Spark Plugs, of which the following is a full, clear, concise, and exact description, such as will enable others skilled in the art 10 to which the invention relates to make and use the same, reference being made therein to the accompanying drawings, which form a part of this specification.

My invention relates to spark plugs designed for use with internal combustion engines to ignite the combustible mixture supplied to the working cylinder thereof; and the principal object or end in view is to provide an improved spark plug having a 20 construction of grounded or shell electrode such that the liability to short circuit will be reduced to a minimum, such end being attained by providing a grounded or shell electrode of such form and which is so arranged 25 relative to the central insulated electrode that such oil or other liquid as may accumulate thereupon will run down and away from the spark gap of the plug, thus maintaining the same in a clean condition at 30 all times.

In internal combustion engines, especially such as are designed to operate upon comparatively heavy hydrocarbons, there is a decided tendency of the fuel used to condense within the cylinder and accumulate 35 upon the spark plug and other internal parts of the cylinder; which condensate, should it accumulate to any considerable extent between the electrodes of the plug, will result 40 in short circuiting the same and in preventing the engine from operating. In my improved spark plug, however, the stationary or shell electrode is of such form and is so arranged that such condensed fuel as may accumulate at the spark gap will naturally run down and away therefrom and fall from the shell electrode, thus maintaining the gap 45 always open and preventing short circuiting of the plug.

The idea of invention above expressed 50 may be carried out in many ways, two of which are illustrated in the drawing accompanying and forming a part of this specification; although it will be appreciated that 55 my invention includes such other specific

forms of stationary electrode as come within the scope of the concluding claims wherein the distinguishing features of my invention are particularly pointed out.

Referring now to the drawing:

Figure 1 is a view showing a section upon a vertical central plane of a spark plug having a grounded or shell electrode made in accordance with my invention.

Figure 2 is a view showing the plug shown in Figure 1 as seen from a position beneath the same.

Figure 3 is a fragmentary view showing the plug as seen from a position at the left of Figure 1.

Figure 4 is a view similar to Figure 1, but showing a slightly modified form of stationary or shell electrode.

Figure 5 is a view showing the plug shown in Figure 4 as seen from a position beneath the same.

Figure 6 is a view at the lower end of the plug shown in Figure 4 as seen from a position to the left thereof.

In the drawing, the reference numeral 10 designates the exterior metallic shell or casing of a spark plug, the same being hollow and adapted to receive the insulating member 11; said insulating member being held in place within the casing by an inturned holding flange 12, as is usual in spark plugs of the single piece variety or type. It will be appreciated, however, that my invention is in no way limited in the manner in which the insulating member is held in place within the casing and is equally applicable to types of spark plugs wherein said member is removable from the casing, and is held therein by a suitable gland nut.

Extending through the insulating member is the usual central electrode 13 of the plug; and the reference 14 designates the grounded or shell electrode. This shell electrode extends, as shown in the drawing downward some little distance below the lower extremity of the central electrode and is bent at right angles, and extends inward and terminates in a position beneath the power end of the central electrode; the bent portion indicated by the reference numeral 15 lying below the level of the spark gap between the extremities of the central and shell electrodes.

The laterally extending portion of the shell electrode is preferably so shaped as to

provide downwardly diverging sides or walls 16, 17, which merge with one another along the upper edge 18 of the horizontal portion 15 to thereby provide a sharp ridge, as best shown in Figures 2 and 3. The apex of the horizontal portion at the extremity thereof lies beneath and provides a comparatively sharp edge opposite the lower end of the insulated electrode; from which it follows that when the plug is in use such liquid as may accumulate upon the grounded electrode due to condensation of the fuel employed or of oil supplied for lubricating purposes will run down the inclined sides 16, 17 and drip from the lower edges thereof; it being understood that the plug will ordinarily be used in a vertical position like that in which it is illustrated. This running down of the condensed liquid will prevent the accumulation of the same at the spark gap and prevent short circuiting of the plug, the result being that the spark gap is kept free at all times from liquid which would otherwise tend to foul and short circuit the same.

In the form of my invention shown in Figures 4, 5 and 6 the construction of the insulator, the central electrode and the external shell or casing is substantially the same as hereinbefore described. The grounded or shell electrode, however, is of somewhat different form; the same comprising a depending portion 19, a substantially horizontal portion 20 extending to a position beneath the central electrode, and an upwardly bent extremity 21 which lies beneath and opposite the lower end of the central electrode. It will be seen that this central portion 20 is disposed below the level of the spark gap so that such oil as may accumulate upon the shell electrode will

run down onto the horizontal part 20 and drip therefrom without accumulating at the spark gap, thus keeping the spark gap free from condensed oil or hydrocarbon and preventing short circuiting of the plug in substantially the same manner as hereinbefore explained. 45

Having thus described and explained my invention, I claim and desire to secure by Letters Patent: 50

1. In a spark plug the combination with a central insulated electrode, of a grounded or shell electrode having an angularly bent portion with diverging sides extending throughout substantially the whole length of said portion, said angularly bent portion being located beneath the central electrode and arranged with its apex upward, so that such oil as may condense upon the same 60 may run down and drip from the lower edges of the sides of said angularly bent portion. 55

2. In a spark plug the combination with a central insulated electrode, of a grounded or shell electrode having a vertical portion extending downward from the shell, and a horizontal portion extending from said vertical portion and to a position beneath the lower end of the central electrode; said horizontal portion being V-shaped in cross section throughout substantially its whole length, and disposed below the level of the spark gap with its apex upward, so that such oil as may condense upon said horizontal portion will run down the sides thereof, thus preventing the accumulation of oil between the extremities of the electrodes and the fouling of the plug. 70 75

In testimony whereof I affix my signature.

ALBERT CHAMPION.
